UNITED STATES PATENT OFFICE

JOSEPH BEHLE, OF DALLAS, TEXAS, ASSIGNOR TO THE MURRAY COMPANY, OF DALLAS, TEXAS, A CORPORATION OF TEXAS

BREAST LIFTER FOR GINS

Application filed December 7, 1929. Serial No. 412,390.

This invention relates to new and useful improvements in breast lifters for gins.

One object of the invention is to provide improved means for lifting a gin breast.

Another object of the invention is to provide compensating resilient means for assisting in lifting a gin breast to be adjusted in proportion to its load.

A further object of the invention is to provide lever locking means for securing a gin breast in lowered and raised positions; whereby accidental displacement from either position is precluded.

A construction designed to carry out the invention will be hereinafter described together with other features of the invention.

The invention will be more readily understood from a reading of the following specification and by reference to the accompanying drawings in which an example of the invention is shown, and wherein:

Fig. 1 is an end elevation of a portion of a gin stand showing the breast closed or lowered and an attachment embodying my invention applied thereto.

Fig. 2 is an end elevation of a portion of a gin stand showing the gin breast in an open or raised position.

Fig. 3 is a side elevation of portions of a gin stand showing the invention as applied thereto, and

Fig. 4 is a detailed sectional view of the lever locking means release.

In the drawings the numeral 10 designates a portion of one of the end frames of a gin stand. The breast 11 is hinged to the stand at 12 and is constructed in the usual way and provided with a lower rib bar 13 and a rest plate 14. These parts are found in the ordinary gin construction and form no part of my invention.

On the lower front side of the gin and below the breast, a longitudinal shaft 15 is mounted in bearings 16 secured to the end frames 10. Oppositely coiled springs 17 are mounted circumferentially of the shaft 15 and adjacent each of the bearings. One end of each spring is secured in the adjacent bearing 16 while the opposite end of each spring is secured to a ratchet 18 loosely mounted on

the shaft. The coil of each spring to its respective ratchet is such that by rotating the ratchet clockwise of the shaft 15, (Fig. 1) the tension of the spring is increased. The springs are preferably square in cross-section whereby greater tensional strength is provided, but, the invention is not to be limited to this particular type as any spring suitable for the purpose may be used.

The ratchets are positioned with their teeth 18' engaging teeth 19' on the hubs of lever arms 19. Said arms are adjustably mounted on the shaft 15 by set screws 20. The outer ends of the arms are yoke shaped and each has mounted thereon a roller 21 by means of a pin 22. The rollers are adapted to engage cam-faced plates 23 secured on the lower end of the breast.

One end of the shaft 15 extends through one of the bearings 16 beyond the end frame 10 and has securely mounted thereon an operating lever 24. The lever 24 extends upward through an elongated slot 28 in a segmental shaped racket 25 secured to the end frame 10 by a bolt 26 and nut 26'. The lever 24 is bent rearwardly and carries a handle 27 at its upper end. By grasping the handle and pulling the lever forward the shaft is rotated counter-clockwise (Fig. 2) thus swinging the arms 19 forward whereby the breast is swung open or raised.

Teeth 29 and 30 are provided on the front and rear ends respectively of the bracket for engagement by a dog 31 carried by the lever 24. A plunger 32 carried in the handle rests on one end of a lever 33 pivoted in a boss 27' of the handle. The outer end of the lever 33 is pivotably connected to the upper end of a rod 34 which has its lower end pivoted in an eye on top of the dog 31. A coiled spring 35 is mounted circumferentially of the dog and confined thereon by a washer 36 secured to the dog and a boss 37 of the operating lever 24 whereby the dog is normally depressed.

By pressing the plunger 32 down the rod is raised whereby the dog 31 is lifted to free it from the teeth of the bracket. By this arrangement the lever 24 may be locked in a forward or rearward position.

By rotating the ratchets 18 clockwise of

the shaft (Fig. 2) the tension of the springs 17 may be increased, thus providing adjustable means for partially counterbalancing the weight of the breast.

5 As the lever 24 rides in the elongated opening 28 of the bracket the actuation of said lever is thereby limited within the length of said opening. Such limited actuation of the lever will prevent the displacement of the 10 rollers 21 from engagement with the cam plates 23.

By grasping the handle 27 and depressing the plunger 32 the lever may be pulled forward thereby raising or opening the breast 15 as hereinbefore explained. The springs 17 being under tension will tend to uncoil and thus assist in the raising of the breast. As the lever is pulled forward the dog 31 will ride over and engage the tooth 29 of the bracket 20 thus locking the lever in a forward position and securely holding the breast in a raised position.

By grasping the handle 27 and depressing the plunger 32 the lever 24 may be pushed rearwardly thereby closing or lowering the breast as hereinbefore explained. As the lever is pushed rearwardly the dog 31 will ride over and engage the tooth 30, thus locking the lever in a rearward position and securely holding the breast in a lowered position.

The lever 24 has sufficient length which with the partial spring tensioned counterbalance provides for the easy and convenient 25 handling of the breast. Obviously, with the spring tensioned counterbalancing means herein described, it is possible by merely rotating the ratchets to vary the tensional strength of the springs thereby providing 40 variable means for assisting in the raising or lowering of the breast.

Various changes in the size and shape of the different parts, as well as modifications and alterations, may be made within the 45 scope of the appended claims.

What I claim, is:

1. In a gin breast lifting device, the combination with a gin frame, a rock shaft, elements carried by said shaft for engaging the breast to elevate said breast when the shaft is 50 rocked, means for rocking said shaft, and oppositely coiled springs surrounding the shaft, each spring having one end immovably held and its opposite end adjustably secured and 55 arranged for rotation whereby the tension of the spring may be varied, said springs being under tension when the breast is lowered and uncoiling when the breast is elevated to assist in lifting the same.

2. In a gin breast lifting device, the combination with a gin frame, a rock shaft, elements carried by said shaft for engaging the breast to elevate said breast when the shaft is 60 rocked, means for rocking said shaft, and oppositely coiled springs surrounding the

shaft, each spring having one end immovably held and its opposite end secured in a ratchet loosely mounted on the shaft and adapted to engage ratchet teeth on the hub of the lifting arm whereby the ratchet may be rotated for varying the tension of the spring, said springs being under tension and connected to the lifting arms assist in the lifting of the breast. 70

3. In a gin breast lifting device, the combination with a gin frame, a rock shaft, elements carried by said shaft for engaging the breast to elevate said breast when the shaft is rocked, means for rocking said shaft, and a coiled spring surrounding the shaft, the 80 spring having one end immovably held and its opposite end adjustably secured and arranged for rotation whereby the tension of the spring may be varied, said spring being under tension when the breast is lowered and 85 uncoiling when the breast is elevated to assist in lifting the same. 75

4. In a breast lifter for a cotton gin, a rock shaft, means for mounting said shaft on the gin stand, elements mounted on the shaft for 90 engaging the breast for lifting the same when the shaft is rocked, a lever secured to the shaft, a locking plunger carried by said lever, a locking segment mounted on the gin frame having stops for receiving said plunger and 95 spaced so as to lock said lever at each end of its swing, whereby the breast may be locked against displacement in both an elevated and lowered position. 95

In testimony whereof I affix my signature. 100
JOSEPH BEHLE.
